UNITED STATES PATENT OFFICE.

DAVID JAS. WHITE AND DAVID H. HANNA, OF OIL CITY, PENNSYLVANIA.

CONTINUOUS FROG FOR RAILWAYS.

1,313,441.

Specification of Letters Patent.

Patented Aug. 19, 1919.

Application filed May 16, 1919. Serial No. 297,595.

To all whom it may concern:

Be it known that we, DAVID J. WHITE and DAVID H. HANNA, citizens of the United States, residing at Oil City, in the county of Venango and State of Pennsylvania, have invented certain new and useful Improvements in Continuous Frogs for Railways, of which the following is a specification.

The primary object of this invention is, to supply a continuous frog for railway tracks whereby the usual gap between the throat and the point of the frog will be obviated, thus avoiding the drop of the car wheel as it passes through the frog.

Another object of our invention is, to provide means for locking the shifting, rail-alining or continuing member in its proper functional position whereby any accidental shifting or displacement of said member is avoided.

The construction whereby we attain said objects is clearly shown in the drawings which form a part hereof, the various figures of which are as follows:

Figure 1 is a plan view of our improved continuous frog.

Fig. 2 is a section on line II—II of Fig. 1.

Fig. 3 is an inside elevation of one of the alining-rails, the connecting cross-piece or guide-block being shown in section.

Fig. 4 is a section on the longitudinal center line of Fig. 1, and on line IV—IV of Fig. 2.

Fig. 5 is a plan view of the sole plate, stripped of the coöperating elements.

Fig. 6 is a plan view of the shiftable, alining-rail structure.

Fig. 7 is a side elevation of the alining-rail structure.

Fig. 8 is a side elevation of the locking-dogs and the actuating block by which both said dogs and said shiftable structure are actuated.

We will now describe the construction illustrated by said drawings, in a manner sufficiently full, clear and exact to enable those skilled in the art of railway-track construction to make and use our continuous frog.

The point of the frog is indicated by the numeral 1. 2 and 3 are the converging rails between which and said point 1 a continuous, alining rail structure is to be supplied. 2' and 3' are the shiftable alining or continuing-rails adapted to form the continuing elements or sections between said converging

rails 2 and 3 and said point 1. Said continuing rails 2' 3' are firmly and rigidly united by means of the guide-block 4. All of said supplementary-rail structure is preferably formed as a unitary structure,—see Figs. 6 and 7.

Said supplementary, or alining rail structure, Fig. 6, is operatively mounted upon a sole plate 5 shown in Fig. 5. A transverse groove is formed in said sole plate for the reception of said guide-block 4. A groove is formed in each of the longer edges of said guide-block 4 for the reception of the retaining plates 8, 8; said plates are attached to the sole-plate 5 in any suitable manner, as by screws 9.

For the purpose of actuating said supplementary, alining rail-structure into its respective alining positions, we provide an actuating block 10 which occupies a groove in the lower face of said guide-block 4, and is adapted to have longitudinal movement therein. Said actuating block 10 is provided with a lug 11 for the attachment of any operating means, 12, suitable for the purpose, and to be determined by the class of service or traffic over the road at the location of the frog. An opening 11' is provided in the sole plate 5 for the reception of said lug 11.

Each end of the actuating block 10 is provided with a cam-lug 13 the inner, opposing faces of which are vertical and adapted to engage the adjacent faces of the abutments 14 of the alining-rail structure. The upper faces of said lugs 13 are formed into outwardly-sloping faces 15, 15 which are adapted to coöperate with correspondingly-formed faces upon the under side of the respective adjacent ends of the locking-dogs 16 and 17, the office of such coöperation being to suitably actuate said dogs, especially out of the locking position into the position occupied by the dog 16, the dog 17 being shown in its locking position. The outer ends of said dogs are hinged to the sole-plate 5, and for this purpose the hinge-pin lugs 19, 19 are provided upon the outer ends of the wings 18, 18. Each of said dogs 16 and 17 is provided in its outer end with a pin-socket 20 for the reception of the hinge-pin 21, whereby said dogs are adapted to have free vertical swinging movement.

The distance between the vertical faces of the actuating lugs 13, as indicated by the dimension α in Fig. 8, is somewhat greater than the distance between the outer faces of the

abutments 14, as indicated by the dimension y in Fig. 7 and as clearly shown in Fig. 2; this difference in said two dimensions provides for the amount of lock-actuating movement 5 indicated at z in said Fig. 2 before said actuating lug 13 comes into contact with abutting face of its respective abutment 14. During said movement z the cam-face 15 impinges upon the corresponding face of the 10 locking dog 17 and causes said dog to rise from its locking position, and thus to permit the shifting movement of the alining-rail structure, which is also accomplished by said actuating block 10 as it continues its 15 movement in the same direction; when this last-mentioned shifting movement is completed, so that the rails 2 and 2' are properly alined, dog 16 drops down and locks the alining structure in its functional position.

20 We claim the following:

1. In a continuous frog for railways, in combination, fixed frog-point, two fixed rails converging toward but not meeting said point, an alining rail-structure comprising 25 two rigidly-united rail members shiftable

to form a continuous rail between either of said converging rails and said point, means operable to shift said rail structure, and means automatically locking said shiftable structure in either of its functional positions. 30

2. A continuous frog for railways comprising in combination, a sole plate, a frog point partially carried by said sole plate, two converging rails, each having its inner edge alined with the opposite outer edge 35 of said point and spaced longitudinally therefrom, a rail structure carried by said sole plate and shiftable to form an unbroken continuation of said inner face of either of said converging rails with the corresponding 40 alined face of said point, a locking means positioned upon each side of said shiftable structure and adapted to lock the same in its respective positions, and means operable both to shift said shiftable structure and to 45 actuate said locks.

In testimony whereof we affix our signatures.

DAVID JAS. WHITE.

DAVID H. HANNA.
